UNITED STATES PATENT OFFICE.

REINHARD E. BARTELS, OF LYNN, MASSACHUSETTS.

SHOE-SHANK STIFFENER AND METHOD OF MAKING THE SAME.

Application filed June 12, 1924. Serial No. 719,679.

Where shoe shank stiffeners are formed from a pair of superposed metal strips having their ends fixed together as by the use of interfitting portions thereof, it is found that even though these strips are initially very securely fastened, they work loose as the shoes are worn and move relative to each other sufficiently to become noisy.

According to the present invention the two parts are put together under stress and united at their ends by spot welding. By this construction the advantages of the two piece stiffeners are retained and at the same time the parts are so united that they can not work loose.

For a more complete understanding of this invention, reference may be had to the accompanying drawings in which

Figure 1 is a side elevation of one of the 20 elements of the stiffener.

Figure 2 is a section on line 2—2 of Figure 1.

Figure 3 is a perspective of the other element of the stiffener.

Figure 4 is a section on line 4—4 of Figure 3.

Figure 5 is a side elevation of the same element.

Figure 6 is a side elevation showing the 30 two elements welded together at one end.

Figures 7 and 8 are a side elevation and plan view, respectively, of the completed stiffener.

One of the elements of the stiffener as shown at 1 in Figure 1 comprises a metal strip molded to a longitudinal and lateral curvature, the lateral curvature being for a portion only of its length to form a convex bead 2 extending along the concave side of the longitudinal curve thereof, leaving a relatively long, laterally flat end 3 and a relatively short, laterally flat end 4. The other element, shown detached in Figures 3, 4, and 5, comprises a flat strip of metal 10 which preferably has formed at its ends integral attaching prongs 11 and 12 by which the stiffener when completed may be fixed to the shoe. However, if it is not desired to use integral prongs, this section, or both sections, may be constructed in any other suitable manner to permit fastening elements for attaching the stiffener in the shoe to be engaged therewith.

As is shown the prongs 11 are of considerable length and are intended to be driven through the heel seat portion of the innersole,

while the prongs 12 are shorter and are intended to be formed so as to be clinched within the material of the innersole without passing therethrough, these prongs being positioned adjacent the forward end of the shank at the "break" line of the sole.

The parts are then assembled as shown in Figure 6, one end of the strip element 10 being placed against one end of the molded strip element 1 on its longitudinally convex side and fixed thereto by spot welding as at 15. As shown in this figure the end of the element 10 having the prongs 11 is placed opposite the end 3 of the element 1, the 70 prongs being outwardly directed. The opposite end of the element 10 is then sprung into position against the end 4 of the element 1 bridging the concave side of the bead 2, as shown in Figure 7, and welded at 16 there- 75 to to form the completed stiffener. The metal may then be treated in any suitable way as by galvanizing to prevent rust. By thus uniting the two elements to form the completed stiffener they become an integral piece 80 so that there is no possibility of the elements becoming detached or working loose when in position in the shoe.

Having thus described this invention it should be evident that various modifications 85 and changes might be made therein without departing from its spirit or scope as defined by the appended claims.

I claim:

1. The method of making a shank stiffener 90 which comprises molding a metal strip to a longitudinal curvature, fixing to one end of said molded strip on its convex side a flat strip, bringing the strips together in superposed relation, and fixing said strips together adjacent to their opposite ends.

2. The method of making a shank stiffener which comprises molding a metal strip to a longitudinal curvature, welding to one end of said molded strip on its convex side a flat 100 strip, bringing the strips together in superposed relation, and welding said strips together adjacent to their opposite ends.

3. The method of making a shank stiffener which comprises molding a metal strip to a 105 lateral and a longitudinal curvature, fixing to one end of said molded strip on its longitudinally convex side a flat strip, springing the strips together in superposed relation, and fixing said strips together adjacent to 110 their opposite ends.

4. The method of making a shank stiffener

which comprises molding a metal strip to a lateral and a longitudinal curvature, welding to one end of said molded strip on its longitudinally convex side a flat strip, 5 springing the strips together in superposed relation, and welding said strips together adjacent to their opposite ends.

5. The method of making a shank stiffener which comprises fixing together at one end 10 a pair of strips of different natural longitudinal curvatures, springing said members together in longitudinally overlying relation, and fixing them together adjacent to their opposite ends while thus sprung together.

6. The method of making a shank stiffener which comprises welding together at one end a pair of strips of different natural 20 longitudinal curvatures, springing said members together in longitudinally overlying relations, and welding them together adjacent to their opposite ends while thus sprung together.

7. A shoe stiffener comprising a pair of 25 superposed metal strips of inherently different longitudinal curvature sprung and welded together adjacent to their ends.

8. A shank stiffener comprising a pair of 30 superposed metal strips of inherently different longitudinal curvature sprung and welded together adjacent to their ends, one of said strips having integral therewith elements for attaching the stiffener to a shoe.

9. A shank stiffener comprising a pair of

superposed metal strips, one of said strips 35 being curved laterally intermediate its ends and substantially flat adjacent to its ends, said strip also having a longitudinal curvature so that the lateral concavity is on the same side as the longitudinal convexity, the other of said strips being substantially flat laterally and bridging the concave side of said one strip, said strips being sprung and welded together adjacent to their ends at their substantially flat portions.

40 10. A shank stiffener comprising a metal strip curved longitudinally, and another metal strip overlying said first strip and sprung to the longitudinal curvature thereof and welded thereto adjacent to its ends.

45 11. A shank stiffener comprising a metal strip curved laterally and longitudinally, and another metal strip bridging the laterally concave side of said first strip and sprung to its longitudinal convexity and welded thereto adjacent to its ends.

50 12. A shank stiffener comprising a metal strip curved laterally for a portion of its length, laterally flat adjacent to its ends and curved longitudinally, and another metal strip bridging the laterally concave side of said first strip and sprung to its longitudinal curvature on its longitudinally convex side and welded thereto adjacent to its ends at its relatively flat portion.

55 In testimony whereof I have affixed my signature.

REINHARD E. BARTELS.
